UNITED STATES PATENT OFFICE.

DAVID McNAIR, OF BOSTON, MASSACHUSETTS, ASSIGNOR TO THE ROXBURY CARPET COMPANY, OF SAME PLACE.

DESIGN FOR CARPETS.

Specification forming part of Design No. 9,376, dated July 4, 1876; application filed June 26, 1876.
[Term of Patent 3½ years.]

To all whom it may concern:

Be it known that I, DAVID McNAIR, of Boston, in the county of Suffolk and State of Massachusetts, have invented a new and original Design for Carpets, of which the following is a specification:

The nature of my design is fully shown in the accompanying photographic illustration.

I claim—

The design for carpets, as shown in the accompanying photographic illustration.

In testimony whereof I have signed my name to this specification in the presence of two subscribing witnesses.

DAVID McNAIR.

Witnesses:

C. F. BROWN,
B. W. LACY.
